United States Patent Office.

L. F. BROWN, OF KEOKUK, IOWA.

Letters Patent No. 69,535, dated October 8, 1867.

IMPROVEMENT IN GATES.

The Schedule referred to in these Letters Patent and making part of the same.

TO ALL WHOM IT MAY CONCERN:

Be it known that I, L. F. Brown, of the city of Keokuk, county of Lee, and State of Iowa, have invented a new and useful Improvement in Gates; and I do hereby declare the following to be a full, clear, and exact description thereof, reference being had to the accompanying drawings, and to the letters of reference marked thereon, in which—

Figure 1 is a perspective elevation of my improved gate, and

Figure 2, sheet 2, is a ground plan, showing the different parts of the same.

The object of this invention is to form a gate which can be opened or closed by a person approaching from either side, before reaching the gate.

This improvement consists in a gate, and the apparatus for operating it, which is made as shown in the drawings, and as hereinafter set forth, using several well-known parts, which can be more or less varied, as desired.

Two sills A A' are laid parallel on the ground, a small distance apart, which join at each end a cross-sill, D D'. The cross-sills D D' extend out in different directions, as shown, parallel to the roadway across which the gate is made. At or between the ends of the sills A A' are posts C C', which are made double, to allow the panels of the gate to be held, and to pass between them for opening and closing. At the out ends of sills D D' are hollow posts, E E', which at their tops contain cross-cylinders fixed on journals that turn in the posts, and have the hand-cranks F F' at their ends, which the person who wants to open the gate can turn for that purpose without dismounting, if riding. At the feet of posts E E' are two pulleys, H I, H' I', each turning freely, and near the posts C C' are two more pulleys each, K K'. Between the sills A A', at each end, are cross-cylinders G G', also turning freely, and in line between the two pairs of pulleys K K'. Now, a rope, L, passes around the cylinder at crank F one or more times, so as to be given off or taken up by turning crank F either way. This rope L passes down inside of post E and over pulley H, thence over one of pulleys K, and around cylinder G one or more times, to insure its turning by the rope, thence over one of the pulleys K', over pulley H', and up post E' to and around cylinder at F' once or more times, for the same purpose as around that at F, whence passing down again as rope L' it passes over pulley I', the other pulley at K', around the cylinder G' once or more times, as at G, over the other pulley at K, and pulley I to the beginning, thus forming an endless cord or belt, arranged for the purpose of turning the cylinders G G' together in opposite directions, so as to run the two panels of the gate B B' together or apart, to open or close. Under each of the panels B B' there is a rope, M M', attached to the two ends of the panel, which ropes respectively pass around cylinders G G' one or more times, so that the turning of the cylinders will pull the panels open or together, or other arrangements of gearing can be used therefor. The frame-bed A A' can be covered for roadway.

What I claim, is—

The cranks F F', with their cylinders, the posts E E', pulleys H I, H' I', K K', the cylinders G G', and rope L L', or their substantial equivalents, combined and arranged as and for the purpose specified.

L. F. BROWN.
